BY *John R. Burch*

Attorney

UNITED STATES PATENT OFFICE.

LILLIE BOGGAN, OF ATKINS, ARKANSAS.

BRACE.

1,031,105.

Specification of Letters Patent. Patented July 2, 1912.

Application filed February 23, 1911. Serial No. 610,174.

To all whom it may concern:

Be it known that I, LILLIE BOGGAN, a citizen of the United States, and residing at Atkins, in the county of Pope and State of Arkansas, have invented certain new and useful Improvements in Braces, of which the following is a specification.

My invention relates to new and useful improvements in obstetrical appliances, 10 more especially for use in parturition or women in child labor.

The invention has for its principal object, among other things, to facilitate the delivery operation and to greatly relieve discomfort.

A further object is to provide a novel device for the above purposes, which will carry out the intended end in an effective manner.

20 Also an object of the invention is to provide an exceedingly simple, readily applied and inexpensive contrivance for effecting the aforesaid purposes.

In the accompanying drawing illustrating 25 the preferred embodiment of my invention, wherein various changes or modifications as relates to details thereof are allowable without departing from the spirit of the invention, provided the same may fall within 30 the scope of the appended claims:

Figure 1, is a perspective view of my invention. Fig. 2, is a like view of portions of the brace members, folded. Fig. 3, is a cross section produced through one of the 35 padded end-bars, and showing portions of the brace members.

In carrying out my invention, I employ what may be termed a brace, as shown, preferably constructed of metal and adapted for 40 disposition or application intermediate of the lower limbs, for service as a brace, as will be disclosed more fully later. Said brace comprises the separable, duplicate members 2, 2^a, which are secured together at 45 one end and extended in V shape, as disclosed, each including longitudinal inclined lateral bars, 3, with their outer divergent ends secured together by an arcuate end-bar, 4, which is formed integral therewith, the 50 curvature thereof conforming to the general

contour of the portion of the limb with which it is designed to contact. The end-bars, 4, are suitably padded as at 5, by securing a suitably filled section of leather or cloth to the portions 3 and 4, for the comfort of the 55 user. The meeting or convergent ends of the brace section 2^a, are brought in contact to form a single piece or extension 6, and is adapted to be received between parallel like extensions, 7, of the other brace-section, 2, 60 and said sections are held in this position by a pivot-pin, 8, and a removable pin, 9, which are disposed through registering openings in the extensions 6 and 7. The removable pin, 9, may be displaced when desired when 65 the brace-sections may be folded as shown in Fig. 2, the same then pivoting upon the retained pivot-pin, 8, for storing, for instance in a portable medicine cabinet or case, as may be desired.

70 Suitable straps, 10, 10^a, are secured to the brace-sections 2, 2^a, adjacent the ends of the padded portions, so as to coöperate with the padded end-bars, 4, of said brace-sections for the application of the brace to the lower 75 limbs, at points just below the knees, the straps 10^a, being provided with buckles or clasps for engagement with the openings in the straps, 10, in effecting such application, as will be readily understood. Additional 80 straps 11, are also secured to the brace-sections 2, 2^a, adjacent to the straps 10^a, said straps having hand-receiving loops, 12, at their outer free ends for enabling the user 85 to conveniently exert a pulling action upon the brace, as in relieving discomfort and facilitating the parturition process or action.

This device is exceedingly simple in construction, readily applied for use, inexpensive to manufacture, and enabling in its 90 action, as is apparent.

Having thus described my said invention, what I claim as new and desire to secure by United States Letters Patent, is:

95 A brace of the character described comprising a pair of triangular shaped frames having the apexes thereof pivotally connected to admit of the frames being folded against each other or swung apart so as to 100

extend in opposite directions, the side of each frame opposite the pivoted apex being shaped to conform to the leg, straps applied to the frames for holding the legs in engagement with the said sides, and means for holding the frames rigidly in a distended position.

In testimony whereof I affix my signature in presence of two witnesses.

LILLIE BOGGAN.

Witnesses:

W. C. TETLER,
J. M. CARPENTER.
